UNITED STATES PATENT OFFICE

CHARLES HENRI CLAUDEL, OF NEUILLY-SUR-SEINE, FRANCE

CARBURETOR FOR INTERNAL-COMBUSTION ENGINES

Application filed December 11, 1924, Serial No. 755,296, and in France October 24, 1924.

The present invention relates to carburetors for internal combustion engines and has for its object to render the essential parts of a carburetor readily accessible and readily 5 removable and replaceable, so that they may be inspected and cleaned with great facility.

According to the invention a carburetor, comprising a system of nozzles communicating freely with an air inlet passage and carried by a removable hollow connecting member fitting tightly into a float chamber, is provided, in which the float chamber and the body of the carburetor containing the air 10 inlet passage are in one piece the connecting member which is adapted to engage with the body containing the air inlet passage without being secured therein being secured to the float chamber by an assembling bolt traversing the chamber axially and capable 15 of being dismounted without removing the float annularly disposed around the bolt.

According to a further feature of the invention the assembling bolt, which is also utilized for securing the cover of the float 20 chamber in position as has previously been proposed, contains axially arranged therein a screw having, at its lower end, a fuel passage, which, contrary to known arrangements, is not regulated by a needle or any other valve 25 but is constituted by a calibrated orifice adapted to control the supply of liquid fuel 30 from the float chamber. Still further features of the invention will be apparent from the following description and will be set out 35 in the appended claims.

In order that the nature of the invention may be clearly understood, a preferred form 40 of the invention will now be described, by way of example with reference to the accompanying drawings, of which:

Figure 1 is a longitudinal axial sectional view of a device embodying the invention, Figure 2 being a corresponding elevational view; Figure 3 is a view of a similar device, 45 showing the main parts of the carburetor sep-

arated or dismounted. Figure 4 is a sectional view on the line C, D of Figure 1, showing the slow speed regulating screw; and Figure 5 is a plan view of the device drawn to the same scale as Figure 2; Figure 1^a is a view 50 illustrating a portion of Figure 1 on a larger scale.

Figure 6 is a view illustrating another portion of Figure 1. Figure 7 is an axial sectional view of a portion of a modified form of the device in which the calibrated slow-speed orifice is situated at a point between the axis of the nozzles and the float chamber, and is thus made more readily accessible. Figures 8 and 9 are partly sectional views of modified 55 forms of the device in which the calibrated slow-speed orifice is transferred to the centre line of the float chamber, or close to the same, in order that it shall be unaffected by variations in the inclination of the carburetor, 60 while being supplied through the main calibrated orifice and being removable independently of the latter. Figure 10 illustrates a device in which the calibrated slow-speed orifice, which is coaxial with the main calibrated orifice, is removable together with the latter. 70

Referring now to Figures 1 to 6, it will be seen that a carbureting chamber 1, float chamber 2 and atmospheric inlet passage 3 75 are formed in a single piece.

A fuel nozzle device is connected with the float chamber by means of a member 5 having a suitable connecting tube 5' provided therein. The member 5 serves to support the nozzle device and is secured in position by means of a special assembling bolt 6 disposed along the centre line of the float chamber, this bolt also serving to secure a rotatable cover 7 comprising a pipe coupling device 13 for the admission of liquid fuel to the float chamber, a filter 14 and needle valve 15 controlled by a float 16. The bolt 6 is hollow and contains a screw 8 having a milled head at its upper end and shaped at its lower end as illustrated in 85 90

Figure 1^a. The screw 8 is provided with a head *t* having an internal chamber into which the fuel flows from the float chamber, through lateral orifices 9 formed in the bolt 6, and 5 through the annular space between this bolt and the head *t* and through the orifices 9' provided in the walls of the latter. The head *t* cooperates with a seat formed in the lower bored part of the bolt 6 below the orifices 9, 10 and a calibrated orifice 10 is formed in this head. When the head *t* rests on its seat, liquid fuel is supplied to the tube 5' in the member 5 and consequently to the fuel nozzle device which comprises a normal speed nozzle 17 and 15 the slow-speed nozzle 11, the latter being supplied through a calibrated slow speed orifice 11'. The slow speed nozzle device is secured by a member 12 removably mounted in the member 5, as shown in Figure 3. The normal 20 speed nozzle 17 is screwed into an element having a hexagonal portion 4 as illustrated in Figure 3, which contains the conduits of the main fuel nozzle and is screwed into the support 5. The whole device comprising the 25 nozzle 17 can thus be removed together with the member 5 by detaching the bolt 6, and can then be separated if desired from the member 5 by unscrewing the element comprising the hexagonal portion 4.

30 A tapered element 21 serving to correct the air supply is controlled by an external handle 22 and is guided at its lower end by a tube 24 screwed or otherwise secured to the air inlet 3, and in view of this construction, the nozzle 17 can readily be removed or replaced.

The air supply at slow speed is regulated by means of a double screw (Figs. 1 and 4). A screw 19 with milled head 19' is screwed into the body of the carbureting chamber 1, 40 and its nonthreaded internal portion serves as a stop for the barrel 18 of the throttle valve in its closed and open positions (Fig. 1). The screw 19 is hollow and threaded internally to receive a screw 20 with milled head 20', the end of the screw being movable lengthwise so as to close more or less a passage extending centrally through the barrel for the admission of air when operating at slow speed, that is, in the closed position of 45 the barrel 18.

A particular feature of the invention consists in the joint provided between the float chamber 2 and the support 5 whereby the device may be cleaned by emptying the said chamber. As shown in Figs. 1 and 5, the socket 25 of the support 5 entering the aperture in the bottom of the chamber 2 is provided with a plurality of longitudinal grooves 25'; the joint between the main body 5 and the chamber 2 is made fluidtight by a packing washer 26 which is tightened by means of the screw 6. The float chamber can be cleaned by loosening said screw, whereby the liquid in the bottom of the chamber together

with all the impurities which it contains will flow out through the grooves 25'.

It will be noted that the screw 8 together with the main calibrated orifice 10 can be inspected or replaced and may even be removed if the barrel 18 is in the closed position, while the engine continues to run at slow speed, since combustible fluid is freely supplied through the passage in the support 5 to the orifice 11' of the slow speed nozzle 11.

The cover owing to its particular construction may be removed for the inspection of the chamber merely by removing the bolt 6, i. e. even during the slow speed running.

As shown in Figures 1 and 6 the apparatus may be enabled to operate in the most favorable conditions at low temperatures. The connecting tube 5' within the support 5 is surrounded by a free space 28 forming a jacket for the circulation of a heating agent which enters through the orifices 29, 29' and is discharged through the orifice 30. It will be observed that the conduit connecting the main calibrated orifice with the fuel nozzle as well as the base of the fuel nozzle, will be the only parts heated by the small quantity of heating fluid, which may consist of the water or the cooling medium serving to cool the engine to which the carburetor is supplying combustible mixture, or of the water or other fluid which has been heated by contact with the exhaust piping.

Since the float chamber itself is not heated it will continue to operate normally even when the temperature of the heating medium rises to an abnormal extent. Furthermore, since the nozzle device itself is heated by direct conduction from its base, the device is not liable to be frozen.

Fig. 7 shows a modification in which the calibrated slow-speed orifice is situated at 11^a, while the slow speed fuel nozzle 11 as the construction above described is disposed coaxially with the suction conduit. The calibrated orifice 11^a is situated at the end of a bolt 31, which is constructed in an analogous manner to the bolt 8 shown in Fig. 1^a and in order to change the said calibrated slow-speed orifice it is only necessary to remove the bolt 31.

Figs. 8 and 9 show further modifications in which the calibrated orifice 11^b is situated upon or near the centre line of the float chamber so that its output will be unaffected in the same manner as that of the main calibrated orifice by any inclined positions assumed by the apparatus. In Fig. 8, the support 5 comprises two ducts 33 and 34; the duct 33 connects the main calibrated orifice 10 with the compound nozzle 17, and the duct 34 connects the slow-speed calibrated orifice 11^b with the slow-speed sprayer 11; the calibrated orifice 11^b is carried by a low-speed nozzle 11; the calibrated orifice 11^b being formed in the screw 32 which is coaxial with the said chamber, while the modification il-

lustrated in Fig. 9 consists simply in that the screw 32 is disposed in a horizontal position. In these two figures, as well as in the preceding, the two calibrated orifices can be removed 5 separately, and may be arranged in series, as shown, or in parallel, so that the main orifice may be changed while the motor is running at slow speed.

Fig. 10 shows an arrangement in which the 10 calibrated slow speed orifice is removable at the same time as the main orifice 10. For this purpose, the bolt 6 has for instance a recess 35 formed in its lower portion, a plug 36 having the calibrated slow speed orifice 15 11^b formed therein being slidably disposed in this recess, and held by a spring 37 upon a seat which separates the two ducts 33 and 34. To provide for the removal of the plug 36 together with the main orifice 10, a detent 20 pin 38 forms a support for the plug 36, so that the latter is maintained in its recess, attached to the screw 6, and may thus be removed with the latter.

Obviously the arrangements hereinbefore 25 set forth are applicable to other types of carbureting devices, such as those comprising butterfly throttling devices or the like and fuel nozzles disposed in series as shown or in parallel.

What I claim and desire to secure by Letters Patent is:

1. A carburetor comprising in combination, a carburetor body and float chamber solidly joined together, a removable cover cap 25 for said float chamber, a removable hollow connecting member fitting tightly on one side within the bottom of said float chamber and laid on other side on the bottom of said carburetor body, a removable hollow assembling bolt fitted through said cover cap and the float and screwed in the corresponding end of said hollow connecting member and a system of spray nozzles carried by the other end of said hollow connecting member and extending into the vaporizing chamber of the carburetor through a suitable orifice.

2. A carburetor comprising in combination, a carburetor body and float chamber solidly joined together, a removable cover cap 30 for said float chamber, a removable hollow connecting member fitting tightly on one side within the bottom of said float chamber and laid on other side on the bottom of said carburetor body, a removable hollow assembling bolt fitted through said cover cap and the float and screwed in the corresponding end of said hollow connecting member and a system of spray nozzles carried by the other end of said hollow connecting member and extending into the vaporizing chamber of the carburetor through a suitable orifice, a removable bolt provided inside said hollow assembling bolt and a calibrated main orifice provided in the lower part of said inner bolt positional between the interior of the

float chamber and the hollow part of said connecting member.

3. A carburetor comprising in combination, a carburetor body and float chamber solidly joined together, a removable cover cap for said float chamber, a removable hollow connecting member fitting tightly on one side within the bottom of said float chamber and laid on other side on the bottom of said carburetor body, a removable hollow assembling bolt fitted through said cover cap and the float and screwed in the corresponding end of said hollow connecting member, a main spray nozzle removably connected to the other end of said hollow connecting member and extending into the vaporizing chamber of the carburetor, and a separately removable slow speed spray nozzle lodged axially within said main spray nozzle.

4. A carburetor comprising in combination, a carburetor body and float chamber solidly joined together, a removable cover cap for said float chamber, a removable hollow connecting member fitting tightly on one side within the bottom of said carburetor body, a removable hollow assembling bolt fitted through said cover cap and the float and screwed in the corresponding end of said hollow connecting member, a main spray nozzle removably connected to the other end of said hollow connecting member and extending into the vaporizing chamber of the carburetor, and a separately removable slow speed spray nozzle lodged axially within said main spray nozzle.

5. A carburetor comprising in combination, a carburetor body and float chamber solidly joined together, a removable cover cap for said float chamber, a removable hollow connecting member fitting tightly on one side within the bottom of said float chamber by a socket provided upon said connecting member and laid on other side on the bottom of the carburetor body, peripheral grooves upon the outer faces of said socket, a removable hollow assembling bolt fitted through said cover cap and the float and screwed in the corresponding end of said hollow connecting member and a system of spray nozzles carried by the other end of said hollow connecting member and extending into the vaporizing chamber of the carburetor through a suitable orifice.

6. A carburetor comprising in combination, a carburetor body and float chamber solidly joined together, a removable cover cap for said float chamber, a removable hollow connecting member fitting tightly on one side within the bottom of said float chamber and laid on other side on the bottom of said carburetor body, a heating
